INVENTOR.
Charles W. Woodson
BY *A. J. Martell*
ATTORNEYS

UNITED STATES PATENT OFFICE.

CHARLES W. WOODSON, OF LOS ANGELES, CALIFORNIA.

EGG POACHER AND PLACER.

Application filed January 14, 1924. Serial No. 686,078.

To all whom it may concern:

Be it known that I, CHARLES W. Woodson, a citizen of the United States, residing at Los Angeles, in the county of Los Angeles 5 and State of California, have invented new and useful Improvements in Egg Poachers and Placers, of which the following is a specification.

My invention is an egg poacher and placer 10 and the main object thereof is to provide such a device by means of which eggs may be properly poached without breaking and conveniently placed on toast or a plate to be eaten. Another object of the invention is to 15 provide an egg poacher and placer which will be simple in construction, efficient in operation and cheap to manufacture.

Other objects and advantages will appear hereinafter, and while I show herewith and 20 will describe a preferred form of construction, I do not limit myself to such preferred form, but that various changes and adaptations may be made therein without departing from the spirit of my invention as hereinafter claimed.

My objects are attained by the device illustrated in the accompanying drawing, in which,

Fig. 1 is a perspective view illustrating a 30 preferred form of my invention in closed position for poaching eggs.

Fig. 2 is a transverse vertical section taken on line 2—2 of Fig. 1 and in the same position as in said figure.

Fig. 3 is a view similar to Fig. 2 but in 35 open position or in the position it assumes in placing the eggs.

Fig. 4 is a partial plan view of my invention.

Similar numerals refer to similar parts 40 throughout the several views.

In the drawing 1 indicates a frame comprising a strap of metal bent in the form of two parallel side members 2 and 3 and 45 rounded end members 4 and 5 and divided transversely in the middle by a partition strip of metal 6, said frame being mounted on four legs 7, two of which are secured to side member 2 and two to side member 3, each leg being secured near an end of a side member.

Pivotedly mounted within the frame 1 within the spaces between the partition 6 and the ends respectively of said frame are 50 a pair of dished egg receptacles 8 and 9 respectively, which receptacles are semi-cir-

cular in cross section. Each receptacle 8 and 9 is composed of two sections 10 and 11, which are quarter-circular in cross section and meet at their inner longitudinal edges 60 to close the receptacle. Each section 10 and 11 is pivoted at its ends at the intersections of its inner and upper edges by screw pivots 12 and 13 which extend loosely through said intersections, the screw 12 seating in the 65 partition 6 and the screw 13 seating in an end member 4 or 5, there being washers 12^a and 13^a, respectively, on said screws between one end of said sections and said partition and between the other ends of said sections 70 and said end members respectively. Strippers 14 and 15 fit within the egg receptacles 8 and 9 respectively, and each stripper is formed in two sections 16 and 17 fitting against the inside at the upper edges of the 75 receptacle sections 10 and 11 respectively, the sections of said strippers being secured at one end to partition 6 and at their other ends to the frame end members 4 and 5 respectively.

A standard 18 is formed with a fork 19 at its lower end which straddles the upper edge of the partition 6 at the middle thereof and the members of said fork are secured to opposite sides of said partition so that 80 said standard stands up from said partition. A sleeve 20 surrounds standard 18 and a spring 21 surrounds the standard above said sleeve, bearing at its lower end against the upper end of said sleeve and at its upper 85 end against a knob 22 secured on the upper end of said standard, which spring normally holds said sleeve in the lowermost position with the lower end against the upper edge of partition. Rods 23 and 24 are 90 connected at their upper ends to lugs 25 and 26 respectively on the upper end of sleeve 20 and at their lower ends to arms 27 and 28 on the inner ends of the sections 10 and 11 respectively of receptacle 8.

Rods 29 and 30 are connected at their upper ends to lugs 25 and 26 and at their lower ends to arms 31 and 32 on the inner ends of the sections 10 and 11 respectively of receptacle 9. A pair of depending arcuate arms 33 and 34 are formed on the upper end of sleeve 20. The receptacles 8 and 9 are provided with perforations 35 in their sections 10 and 11.

The device is placed in a kettle of water 110 and an egg broken in each receptacle 8 and 9 and poached therein. The device is then

removed from the kettle, (the water passing out of said receptacles through the perforations 35), and placed over two pieces of toast or over a plate, whereupon the operator 5 places the palm of one hand upon knob 2 and with his first two fingers pulling upwardly on arms 33 and 34 raises the sleeve 20 against the tension of the spring 21, which, in turn, through rods 23 and 24 and 10 rods 29 and 30, swings the sections 10 and 11 of receptacles 8 and 9 respectively upwardly 90°, as shown in Fig. 3, and the eggs are stripped by strippers 14 and 15 from said receptacles and delivered therefrom and 15 placed on the toast or plate.

Upon releasing the arms 33 and 34 the spring 21 returns the parts to their normal position as shown in Figs. 1, 2 and 4.

Having thus described my invention what 20 I claim as new and desire to secure by Letters Patent is:

1. A device as disclosed including a frame, a receptacle pivotally mounted in said frame in which eggs are poached, a standard up- 25 standing from said frame, a sleeve slidable on said frame, a knob on the upper end of said frame, a spring surrounding said rod above said sleeve and bearing at its ends against said sleeve and said knob, arms on 30 said sleeve to be engaged by the fingers to lift the sleeve against the tension of said spring, and rods connected to said receptacle and to said sleeve for swinging said receptacle on its pivot for dumping said receptacle when 35 said sleeve is lifted.

2. A device as disclosed including a frame,

a dished receptacle split longitudinally into two sections for poaching the eggs, said sections being pivoted at their meeting corners to said frame, a standard upstanding from 40 said frame, a sleeve slidable on said standard, a knob on the upper end of said standard, a spring surrounding said standard above said sleeve and bearing at its ends 45 against said sleeve and said knob, arms on said sleeve to be engaged by the fingers to raise said sleeve against the tension of said spring, and rods connected to said sections and to said sleeve for swinging said sections apart to deliver the egg from said receptacle when said sleeve is raised.

3. A device as disclosed including a frame, a dished receptacle split longitudinally into two sections for poaching the eggs, said sections being pivoted at their meeting corners to said frame, a standard upstanding from 55 said frame, a sleeve slidable on said standard, a knob on the upper end of said standard, a spring surrounding said standard above said sleeve and bearing at its ends 60 against said sleeve and said knob, arms on said sleeve to be engaged by the fingers to raise said sleeve against the tension of said spring, and rods connected to said sections and to said sleeve for swinging said sections apart to deliver the egg from said receptacle 65 when said sleeve is raised, and a stripper engaging the inside of said sections for stripping the eggs from the receptacle when said sections are swung apart.

CHARLES W. WOODSON.
